(Continued)

Primary Examiner — Llorellys Martinez-Rivera*Assistant Examiner* — Nicole M. Leech(74) *Attorney, Agent, or Firm* — Benjamin C. Rothermel, Esq.(57) **CLAIM**

The ornamental design for a hexagon raised garden bed, as shown and described.

DESCRIPTION

FIG. 1 is a front perspective view of a hexagon raised garden bed showing my new design;

FIG. 2 is a left side perspective view thereof;

FIG. 3 is a top view thereof, the bottom view being a mirror image thereof;

FIG. 4 is a front elevation view thereof, the rear elevation view being a mirror image thereof; and,

FIG. 5 is a cross sectional view taken from portion 5-5 in FIG. 1.

The broken lines in the drawings represent portions of the hexagon raised garden bed and form no part of the claimed design.

1 Claim, 4 Drawing Sheets(56)
